UNITED STATES PATENT OFFICE

2,071,539

POWER FEED FOR DRILLING MACHINES

Edward Joslin Kingsbury, Keene, N. H.

Application September 7, 1934, Serial No. 743,153

8 Claims. (Cl. 77—32)

This invention relates to improvements in power feeding mechanism for apparatus such as drilling machines.

One of the features of the present invention is the provision of a power feeding mechanism including a differentiating gearing which operates while the parts turn together to effect a rapid forward traverse movement, and while differentiating action is occurring to produce a slow working feed, in association with clutch means for engaging the gearing with the tool spindle for the forward movements and for disengaging the same to permit a return movement of the spindle.

Another feature of the present invention is the provision of a power feeding mechanism including a continuously rotating body and differentiating gearing including a planet pinion carried bodily with said body; and sun gears, one of which is operatively connected during the forward feeding movement with the spindle feeding elements and the other may rotate freely in one direction for the rapid feeding movement but is prevented from rotation in the other direction and thereby produces a slow working feed through the action of the differentiating gearing.

A further feature of the present invention is the provision of a power feeding mechanism including an element which is moved in proportion to the feeding movement of the spindle and is provided with resilient stops which are adjustable for determining the limits of movement of the spindle, these stops being operative upon the control mechanism which produces reversal of traverse and feeding movements, and mechanism for bringing the spindle to a standstill at the completion of a cycle.

Still another feature of the present invention is the provision of a power feeding mechanism including a selective driving train for producing rapid and slow forward movements, means for returning the spindle when the train is entirely disconnected, and an electromagnetically operable device for producing a connection of the train, along with circuit means for initiating and maintaining the energization of the electromagnetic device during the forward stroke, and interrupting the same at the limit of the forward stroke so that the disconnection occurs and the spindle is withdrawn from the work.

With these and other features as objects in view, as will appear in the course of the following specification and claims, an illustrative form

of practicing the invention is set out on the accompanying drawings.

In these drawings:

Fig. 1 is a front view of the mechanism head of the apparatus.

Fig. 1a is an upright sectional view substantially on line 1a—1a of Fig. 1.

Fig. 2 is a left-hand side elevation of the structure in Fig. 1, with a guard cover removed, and parts broken away.

Fig. 3 is a corresponding right-hand side elevation.

Fig. 4 is a horizontal section substantially on line 4—4 of Figs. 1, 2, and 3.

Fig. 5 is an upright section substantially on line 5—5 of Figs. 2, 3, and 4.

Fig. 6 is a similar upright sectional view on line 6—6 of Figs. 2, 3, and 4.

Fig. 7 is a fragmentary upright section on line 7—7 of Fig. 5, on an enlarged scale.

Fig. 8 is a fragmentary horizontal section substantially on line 8—8 of Fig. 6, on an enlarged scale.

Fig. 9 is a diagram showing the various circuits and the controls associated therewith.

In these drawings the mechanism head of an upright drill is illustrated as having a general housing casting H with proper internal web walls for the mounting and supporting of the parts as disclosed hereinafter, a front wall for receiving certain control structures, right-hand and left-hand side walls with openings therein to be closed by the right-hand and left-hand cover plates R.C and L.C, and a rear wall including an inclined guideway GW upon which may move a support member SM including upright portions MS on which is fixed a driving motor M as illustrated in my copending application Serial No. 684,063 filed August 7, 1933.

This mechanism head is supported upon a hollow column C which likewise may receive a knee for supporting the work, etc., in the usual manner.

A driving pulley 20 is keyed or splined on a spindle 21 which is illustrated as extending vertically downward through the head H and supported by appropriate bearing 22 (Fig. 1a) in a quill 23 which is guided for vertical and non-rotating movement in the mechanism head H, and is provided with a rack portion 24 in mesh with the quill pinion 25. The spindle has its lower end projecting from the head H and is connected in suitable manner to a tool such as a drill, for driving the same in rotation.

Likewise, a power-driven vertical shaft 30

25

40

45

50

55

(Figs. 2 and 4) is secured to a worm 31. This worm 31 meshes with a worm wheel 32 (Figs. 5 and 6) which forms part of a rotatable body 33 supported by a bearing 34 upon a cylindrical surface 35 of a fixed shaft 36. An open end of the body 33 is closed by a gear structure 37 rotatable relative thereto and supported by bearings 38 engaged on a cylindrical portion 39 of the shaft 36. The body 33 supports the journal pin 40 having a bearing bushing 41 and a double pinion 42 thereon: one element of the double pinion engages with the gear teeth 43 on gear member 37, while the other member of the double pinion engages with gear teeth 44 upon the external overrunning-clutch member 45 (Fig. 7), which has a cylindrical internal surface. The overrunning-clutch structure includes a portion 46 of the fixed shaft 36 which has illustratively three notches 47 (Fig. 7) formed therein to receive the clutch rollers 48 which operate between the surfaces of the notches 47 and the internal cylindrical surface of the clutch member 45 in the normal manner to prevent relative movement in one direction, while permitting a free relative movement in the opposite direction.

The fixed shaft 36 is supported in a portion Ha of the general housing H of the mechanism head, a key 49 (Fig. 5) being provided to prevent rotation of the shaft 36, and a screw 50 passes through the closing guard cover LC and engages in the shaft 36 for drawing it toward and holding it in the left-hand position (Fig. 5) as determined by the engagement of the shoulder provided by its portion 46 with the axle race of the bearing 34, which in turn engages against the structure Ha. The free end of the shaft 36 is provided with threads 51 for receiving an adjustment nut 52 which engages one of the pressure plates 53 which determine the tension and operation of the spring 54.

The gear member 37 has a cylindrical surface 55 providing a plain bearing for the open end of the body 33, and also has the aforesaid gear teeth 43, a surface 56 cooperative with the end surface of the body 33 as a friction means for determining rotation of parts in one direction as will be described hereinafter, and gear teeth 57 of pitch diameter larger than the pitch diameter of gear teeth 43. The axle races of bearings 38 are spaced by a washer 58, and one pressure plate 53 operates to cause these bearings to engage against an internal shoulder 59 of gear member 37 and cause the friction surface 56 to bear forcibly against the end surface of the body 33. It will be noted that the body 33 has an internal shoulder 60 which limits its leftward movement in Fig. 5, by engagement with the axle race of bearing 34.

The gear teeth 57 of gear member 37 engage with a gear 65 mounted on a bearing sleeve 66 and thus loosely rotatable about the axis of the pinion shaft 67 to which is secured the quill pinion 25 (Fig. 6). This shaft 67 has splines thereon for receiving the clutch member 68 having a groove 69 for engagement by the clutch fork lever 70 for moving the clutch member 68 endwise. In one position (Fig. 6) the clutch teeth 71 engage with corresponding teeth on the gear 65. In a central position, the clutch member 68 is free of any clutch engagement. In a right-hand end position the clutch teeth 72 are engaged with similar teeth on a sleeve 73 which extends through the closing guard plate RC (Fig. 6). Secured externally of the sleeve 73 is a collar 74. Extending from this collar 74 is a rod

75. There is an anti-friction bearing 76 between the sleeve 73 and the guard plate RC. When the clutch teeth 72 are moved to the right (upon shifting of the control lever ML as shown in Figure 1 for producing a movement of the support 70a of clutch lever 70, for example) so as to engage the clutch teeth 73a on the sleeve, then the shaft 67 is locked to the sleeve 73, and it may be turned manually. When, however, these clutch teeth are released, then the shaft 67 rides freely in the sleeve 73. This provides a means whereby the pinion shaft 67 may be rotated in the sleeve 73 or may be manually turned through the aid of the sleeve 73. The shaft 67 is supported in anti-friction bearings 77 carried on peripheral flange extensions of the web wall HB of the housing H. The inner end of the pinion shaft 67 has secured thereto a sprocket member 78 which is held in position by a nut 79.

The weight of the spindle, gear and associated parts is counterbalanced by a large weight LW (Fig. 3) which may move upwardly and downwardly in the hollow column C, and is connected to the balance chain BC which passes over a guide sprocket 85 loose on the shaft 86, a driven sprocket 88, the sprocket 78, and a further guide sprocket 87, and is connected at its other end to a small weight SW which maintains the chain tight. The proper proportioning of the weights LW and SW permits accurate compensation of the weight of the parts. It is preferred to have the weight LW sufficiently massive to accomplish an automatic gravitationally-produced raising of the spindle when its power-effectuated downward feeding movement has been concluded.

The movement of the driven sprocket 88 is employed according to the present invention in determining the limits of upward and downward movement of the spindle. For this purpose as shown in Fig. 5, the sprocket 88 is pinned to a flange piece 90 which in turn is keyed to the reduced end of the shaft 91 and is held thereto by a nut 92. The shaft 91 is journaled in a bushing 93 supported in an internal web wall of the housing H. A pin 94 connects the shaft 91 with a limit member 95 having a radially projecting finger 96 whose path of movement causes it to encounter an inwardly extending lug 97 located in a groove of a worm wheel 98. A second worm wheel 99 has a lug 100 which is presented in the path of movement of a pin 101 carried by the flange member 90. Thus, as the sprocket 88 is driven, the flange member 90 carries its pin 101 and the member 95 carries its finger 96 in rotational movement with the shaft 91 through a distance which is proportionate to the rotational movement of the gear pinion 25 and hence proportionate to the upward and downward movement of the spindle itself.

A worm 105 meshes with the worm wheel 98 (Figs. 2 and 5) and is fixed on a rotatable and endwise movable control shaft 106 (Fig. 4) by a pin 107. The shaft 106 is supported by a sleeve 108 which in turn is mounted for rotation and axial guiding in a web wall Hc of the housing H, and is provided with a pin 109 engaged in an axial groove 110 of the shaft 106. The sleeve 108 is also guided in an aperture 110 in the front wall of the head H. The front end (at the right in Fig. 4) of the shaft 106 is provided with a collar 111 fixed thereto, and operating as an abutment for a coil spring 112 located within an annular space provided in the sleeve 108, and abutting at its other end against this sleeve for producing a relative leftward movement of the

sleeve 108 and rightward movement of the shaft 106 in Fig. 4. The sleeve 108 extends through the aperture 118 and is provided externally with a flange 113 having a conical peripheral surface which conforms to a similar surface provided on the split supporting ring 114 which is secured to the face of the housing H by screws 115, so that the parts cooperate to prevent a withdrawal of the sleeve 108 from the housing H. A handle plate 116 with a handle 117 is secured to the flange 113 by screws 118. The flange 113 turns in the split ring 114, and the tightness of its fit may be controlled by adjusting the closing screw 119 of this split ring.

15 At its inner end (at the left in Fig. 4) a structure 125, providing spaced collars, is secured to shaft 106 by a pin 126. In Fig. 2, these collars receive between them the pins 127 of a crank lever 128 mounted on a pin 129 extending from 20 the housing structure H, and provided with a pivot connection 130 to a link arm 131 which extends downwardly into a dash pot D which may be adjusted externally of the head. This dash pot and its associated parts may, however, be 25 omitted when the structures are relatively light and the inertia effects are not great.

In similar manner, the worm wheel 99 is in mesh with a worm 135 secured by pin 136 on a shaft 137 which may rotate and move axially. 30 This shaft 137 is supported in a sleeve 138 similar to sleeve 108 and having a pin 139 engaged in an axial groove 140 of the shaft 137. The end of shaft 138 is provided with a collar 141 forming an abutment for a coil spring 142. The 35 end of sleeve 138 projects through an aperture into the upright front face of the housing H and is provided externally of the housing with a flange 143 which has a conical peripheral surface engaged by a conforming internal surface of an 40 annular supporting plate 144 which is secured to the housing H. A handle plate 146 with a handle 147 is secured to the flange 143 by screws 148. The rear end (at the left in Fig. 4) of shaft 137 is operatively connected with a limit switch 45 RL.

The bifurcated clutch lever 70 (Figs. 2 and 6) is pivotally connected at its upper end by a link 152 to a slide member 151 (Figs. 6 and 8) which is guided in the structure H_b and is pivotally connected at its other end to a link 152 extending from an arm 153 connected by pin 154 to a rock shaft 155 carried by a structure 156 which is aligned by pins 157 (Fig. 3) and secured by screws 158 within the housing H. An upper sleeve 159 rests upon structure 156 and receives a screw 160 which engages a groove 161 in the upper end of shaft 155 to hold this shaft against downward movement, while permitting a free rocking thereof. The pivot pin 162 which connects the link 152 with crank arm 153 also receives a link 163 which connects it with the plunger 164 (Fig. 8) of a solenoid ES. This solenoid is illustrated as of the type shown in the copending application of Benjamin N. Foster, Serial No. 741,341, filed August 24, 1934, (now United States Patent No. 1,987,555). When energized, the plunger 164 draws the arm 153 and link 152 into line so that forces acting in the direction of slide member 151 do not effect any 60 substantial movement. When de-energized, the return spring 165 operates to break the toggle and permit and assist the return movement of slide member 151.

The circuit diagram in Figure 9 shows the connection of certain electrical portions in the ap-

paratus. As shown in Figure 1, the apparatus may be provided at the front of the mechanism head with "Stop" and "Start" push buttons, at a point where they are easily accessible to the operator.

To start a cycle of movement, the operator depresses the "Start" push button and this closes (Figure 9) a circuit from a main conductor 200 through the "Start" button and conductor 202 to a winding 203 of a control relay CR, and thus 10 back to the other main conductor 201. As shown in Figure 3, the relay CR is preferably located within the mechanism head in close association with the other parts of the structure.

The energization of coil 203 causes the relay CR 15 to close and thereby establishes a maintaining circuit from conductor 208 by conductor 204, the normally closed "Stop" button, conductor 205, limit switch RL, conductor 206, bridge 207 of relay CR, and thence through the coil 203 to the 20 main conductor 201. At the same time the relay CR sets up an initiating circuit from main conductor 200 by conductor 208, bridge 209, conductor 210, the winding of solenoid ES and thus back to the main conductor 201. This solenoid ES is energized and a cycle of movement begins, comprising the downward stroke of the spindle 21. At the limit of movement, as determined by the feed control system described herein, the limit switch RL is opened. The maintaining circuit 30 through conductors 204, 205, 206 is interrupted and the relay CR is de-energized and moves to open position, resulting in a de-energization of the solenoid ES so that this solenoid now operates to release the clutch connection 71 and free the 35 spindle shaft 67 from the feed drive. The spindle 21 is returned by the gravity action of the weight LW to its upper position and remains therein until the "Start" button is again depressed. During the return movement of the 40 spindle, the limit switch RL again closes.

It will be noted, however, that the operator has instantaneous control over the apparatus as he may at any time depress the "Stop" button which is in series with the limit switch RL and thus accomplish an immediate stoppage, in similar manner, of the downward feeding movement of the spindle 21, with a return of the spindle to its upward position again by the action of its counterweight LW.

In operation, the attendant releases the split rings 114 and 144 and moves the handles 117 and 147 until the desired adjustment of the stop fingers 87 and 100 is attained, for determining the upper and lower limits of travel of the spindle in 55 its feeding movements. The rings 114 and 144 are then clamped again. The apparatus is thus adjusted to the particular work at hand.

After positioning a piece of work in the usual way, the operator depresses the "Start" button 60 so that the solenoid ES attracts its core and brings the arm 153 and link 152 into alignment with one another so that they thus operate to move slide member 161 and rock the clutch lever 70 so that the clutch elements 71 are engaged. 65 The continuous rotation of the main feed shaft 30 causes the worm 31 to rotate the worm wheel 32 and therewith the body 33. During this initial phase of rapid forward traverse movement, the frictional engagement at surfaces 58 causes 70 the body 33 to rotate the gear body 37 at its own speed, this movement being transmitted through gear 65 and clutch elements 71 and 68 and thus to the quill shaft 67 and to the quill pinion 25, and thus the quill and spindle 21 are moved down- 75

wardly at a relatively rapid rate while the counterweight LW is raised. The movement of the chain BC causes the sprocket 86 also to be rotated and therewith the shaft 91 with fingers 96 5 and 101.

When the tool strikes the work and thus a greater resistance is opposed to the downward movement of the spindle 21 and the quill 24, the back pressure exerted through quill pinion 25, 10 shaft 67, gear 65 to the gear teeth 67 overcomes the frictional engagement at surface 56, so that the body 33 overruns the gear body 37. This, however, causes a relative movement of the pin 40 15 with respect to the gear body 37 and thus the double pinion 42 tends to revolve upon its pin by traveling on gear teeth 43, 44. The turning movement, however, tends to cause a relative counter-clockwise movement of the gear teeth 44 about their central axis (Figure 7) which is resisted by the rollers 62. Thus the double pinion 42 20 is compelled to turn at a rate which is determined, for the particular physical structures, by the speed of movement of the body 33 and this movement is transmitted to gear teeth 43 and thus to the gear body 37. It will be understood that suitable numbers of teeth and pitch diameters are employed for gears 43 and 44 and in double pinion 42, according to the relative speed to be attained 25 during this slow working feed. Thus there may be thirty-two gear teeth 43, thirty-eight gear teeth 44, thirteen teeth on pinion 42 in mesh with gear teeth 43, and sixteen teeth on pinion 42 in mesh with gear teeth 44, to give a ratio of 28.44 to 1 between rapid traverse and slow working feed 30 movements. The continued upward movement of the gear body 37, but at the lesser rate continues to produce a downward movement of the spindle 21 at a consonantly lesser rate, and the tool is advanced into the work at this rate.

40 This working feed continues until the finger 101 encounters the lug 109 on worm wheel 99 and causes a rotation of the worm wheel 99. This rotation is transmitted to the screw 136 and causes a movement of the rod 136 against the 45 action of spring 142, and results in the opening of the limit switch RL, and thus determines the nature of the downward movement of the spindle 21.

The solenoid is de-energized and the clutch 50 elements 71 are moved out of engagement as described above, so that the shaft 67 is now fed from the power drive from shaft 30 and is returned by its counterweight LW which at the same time operates to move the shaft 91 backwardly. The limit of this backward movement 55 is determined by the engagement of finger 96 with lug 97, causing a slight rotative movement of the worm wheel 99 which is transmitted to screw 105 and absorbed by spring 112. As illustrated, this action may be damped by employing the dash pot system 128-131 and dash pot D.

The cessation of the resistance back through the gear train and gears 65-57 permits the frictional surface to operate again and the differential system including the body 33 and its parts 60 then causes the gear body 37 to turn with an equiangular movement as before.

The sensitiveness of translation from the rapid forward traverse to the slow working feed is determined by the compression of spring 54 as adjusted by nut 52.

It is obvious that the invention is not limited solely to the form of construction shown but that it may be modified in many ways within 75 the scope of the appended claims.

Having thus described the invention, what I claim as new and desire to secure by Letters Patent is:

1. A device of the class described, comprising a frame, a member to be advanced relative to 5 said frame at varying predetermined speeds, a shaft having an overrunning clutch surface and means for preventing retrograde movement of the shaft relative to the frame, a differentiating gear train including a body rotatable about said 10 shaft and having an eccentric pivot, a first sun gear freely rotatable about said clutch surface in one direction, a second sun gear connected with said member, and a double planet pinion on said pivot and meshing with said gears and operative to produce a retrograde effect upon said 15 first sun gear relative to said shaft when said body moves relative to said second sun gear, said second sun gear having friction means cooperative with said body for effecting a conjoint equiangular movement of the body, pinion and sun gears when the resistance to movement of said body is less than a predetermined value for producing a high advancing speed of said member, and clutch means cooperative with said clutch 20 surface and said first sun gear to prevent retrograde movement thereof by said planet pinion when the said resistance exceeds said predetermined value so that the differentiating train produces a slow advancing speed of said member. 30

2. A device of the class described comprising a frame, a member to be moved downward relative to the frame, counterbalance means for returning the member upwardly, a shaft and means 35 for preventing retrograde movement of the shaft relative to the frame, a body moved in rotation, a first sun gear freely rotatable in one direction about the shaft, a second sun gear rotatable about the shaft, a double planet pinion 40 pivoted on said body and in mesh with said gears and operative to produce a retrograde movement of said first sun gear relative to said second sun gear when said body moves relative to said second sun gear, said second sun gear having friction 45 means cooperative with said body for effecting a conjoint equiangular movement of the body, pinion and sun gears when the resistance to downward movement of said member is less than a predetermined value, connecting means including a first clutch for connecting said second sun gear for moving said member downwardly, and clutch means engaging the first sun gear and shaft to prevent retrograde movement of said first sun gear relative to said shaft when the said 50 resistance exceeds said value, said first clutch being effective in one position for connecting said second sun gear and member for producing a downward movement of said member and when in another position serving to interrupt said connection so that the counterbalance means may return said member to its raised position. 55

3. A device of the class described, as in claim 2, including means actuated by the member at a predetermined position of downward movement 60 for moving said clutch to the interrupting position.

4. A device of the class described, as in claim 2, including a circuit closer, electromagnetic means for moving said clutch to connecting position, 70 and circuits connecting the closer and electromagnetic means including means for maintaining the energization of the electromagnet during the downward movement of said member, and means operated by said member at a predeter- 75

- mined position of downward movement for de-energizing said electromagnet so that said clutch will move to interrupting position and said counterbalance means will return said member.
- 5 5. A device of the class described comprising a frame, a member to be advanced relative to the frame at varying predetermined speeds, a shaft fixed to the frame, an element moving about the shaft continuously in the same direction, a first gear journaled on the shaft for turning freely with said element in a forward direction, means for preventing retrograde motion of said first gear relative to the frame, a second gear journaled on the shaft, means including a clutch for connecting said second gear to said member to produce advancement of the latter, friction means for causing said element and second gear to turn together when the resistance to advancing movement of said member is below a predetermined value, means cooperating with said element and said gears for producing a relative retrograde effort on said first sun gear when said resistance exceeds said value and thereby operating for effecting a slow continued advancing movement 20 of said second gear and member, and means operated at a predetermined point of advancement of said member for disconnecting said clutch.
6. A device of the class described comprising a frame, a member to be advanced relative to the frame at varying predetermined speeds, a shaft fixed to the frame, an element revolving about the shaft continuously in the same direction and at substantially the same velocity, a first gear journaled on the shaft to turn freely with said element, clutch means on the shaft and first gear effective at all times for preventing retrograde movement of said first gear relative to said shaft, a second gear connected for moving said member, constantly operating friction means for causing said element and second gear to turn together at a rapid rate when the resistance to movement of said member is below a predetermined value, and means cooperating with said element and said gears for producing a relative retrograde effort on said first gear when said resistance exceeds said value and thereby cooperating with said preventing means for effecting a slow continued advancing movement of said second gear and member.
- 50 7. A device of the class described comprising a frame, a member to be moved relative to the

frame, a shaft fixed to the frame, an element revolving about the shaft continuously in the same direction and at substantially the same velocity, planet pinion means carried bodily in movement with said element, a first sun gear in mesh therewith and freely revoluble about the shaft in the direction of movement of said element, clutch means on the shaft and first gear for preventing retrograde movement of said first sun gear relative to the shaft, a second sun gear having a lesser number of teeth than said first sun gear and in mesh with said planet pinion means and having constant frictional engagement with said element to be turned at equi-angular velocity therewith when the resistance to movement of said second sun gear is less than a predetermined maximum, and means connecting said second sun gear and member for advancing said member, said planet pinion means operating to produce a retrograde movement of 20 said first sun gear relative to said second sun gear when the resistance exceeds said maximum.

8. A device of the class described comprising a frame, a member to be advanced relative to the frame, a shaft fixed to the frame, a revolvable element providing a planetary body and means for driving the same in rotation about the shaft, planet pinion means eccentrically mounted on said planetary body, two sun gears each in mesh with said planet pinion means and each 30 rotatable about the shaft, devices connecting said one sun gear with said member to advance the same, friction means for causing said body to turn one said sun gear and devices and advance said member at a fast rate so long as the 35 resistance to advancement of said member is below a predetermined maximum, said body, pinion means and sun gears being constructed and arranged for producing a relative forward movement of the said one sun gear relative to the 40 other said sun gear upon slippage of said friction means, and overrunning clutch means on the other said sun gear and the shaft for preventing retrograde movement of said other sun gear relative to said shaft whereby to cause a 45 slow rate of advancement of said member by said devices, said overrunning clutch means operating to permit movement of said other sun gear with the planetary body during drive through said friction means.

EDWARD JOSLIN KINGSBURY.
